[57] CLAIM

The ornamental design for a petticoat pillowcase with drawstring, as shown and described.

DESCRIPTION

The cross-hatching represents conventional fabric and is understood to extend throughout the areas represented.

FIG. 1 is a front elevation view of a petticoat pillowcase with drawstring showing my new design;

FIG. 2 is a rear elevation view thereof;

FIG. 3 is a top plan view thereof;

FIG. 4 is a bottom plan view thereof;

FIG. 5 is a right side elevation view thereof, the opposite side being substantially a mirror image thereof; and,

FIG. 6 is an enlarged front view of a portion of the petticoat pillowcase with drawstring.

FIG. 1

FIG. 3

FIG. 4

FIG. 6
